UNITED STATES PATENT OFFICE

**CHARLES A. XARDELL, OF UTICA, NEW YORK, ASSIGNOR TO UTICA CUTLERY COMPANY,
OF UTICA, NEW YORK, A CORPORATION OF NEW YORK**

DESIGN FOR A KNIFE

Application filed March 5, 1931. Serial No. 38,942. Term of patent 3½ years.

To all whom it may concern:

Be it known that I, CHARLES A. XARDELL, a citizen of the United States, residing at Utica, in the county of Oneida and State of New York, have invented a new, original, and ornamental Design for a Knife, of which the following is a specification, reference being had therein to the accompanying drawings.

In the accompanying drawings Fig. 1 is a side view and Fig. 2 is a section on line 2—2, Fig. 1, of the newly designed knife.

I claim:

The ornamental design for a knife, as shown.

In testimony whereof I affix my signature.

CHARLES A. XARDELL.
